BOX FOR STORING AND PRESERVING GARMENTS OR SIMILAR ARTICLES

Joseph J. Kearn, San Francisco, Calif.

Application January 13, 1958, Serial No. 49,208

Term of patent 7 years

(Cl. D58—12.6)

Fig. 1 is a perspective view of a box for storing and preserving garments or similar articles embodying my new design,

Fig. 2 is a plan view of the cover only of said container.

Fig. 3 is a side elevational view thereof;

Fig. 4 is an end elevational view thereof;

Fig. 5 is a bottom plan view of the body portion thereof; and

Fig. 6 is a fragmentary cross-sectional view thereof taken on the line VI—VI of Fig. 2.

I claim:

The ornamental design for a box for storing and preserving garments or similar articles, substantially as shown.
